CLAIM

The ornamental design for a label sheet assembly with improved printer feeding, as shown and described.

DESCRIPTION

FIG. 1 is a front view of a first embodiment of a label sheet assembly with improved printer feeding showing our new design;

FIG. 2 is a back view of FIG. 1 thereof;

FIG. 3 is a first side view of FIG. 1 thereof;

FIG. 4 is a second side view of FIG. 1 thereof;

FIG. 5 is a top view of FIG. 1 thereof;

FIG. 6 is a bottom view of FIG. 1 thereof;

FIG. 7 is a front view of a second embodiment of a label sheet assembly with improved printer feeding showing our new design;

FIG. 8 is a back view of FIG. 7 thereof;

FIG. 9 is a first side view of FIG. 7 thereof;

FIG. 10 is a second side view of FIG. 7 thereof;

FIG. 11 is a top view of FIG. 7 thereof; and,

FIG. 12 is a bottom view of FIG. 7 thereof.

The first side, second side, top, and bottom views include a shape and appearance that would be evident from the views of the label sheet assembly as shown.
